UNITED STATES PATENT OFFICE.

VINCENT BENDIX, OF CHICAGO, ILLINOIS.

ENGINE-STARTER.

1,274,373.

Specification of Letters Patent.

Patented Aug. 6, 1918.

Application filed June 18, 1917. Serial No. 175,430.

To all whom it may concern:

Be it known that I, VINCENT BENDIX, a citizen of the United States, residing at Chicago, in the county of Cook and State of Illinois, have invented certain new and useful Improvements in Engine-Starters, of which the following is a specification.

My invention relates to that general class of engine starter exemplified in patents here-
10 tofore issued to me, for instance, Patent No. 1,116,370, dated November 10, 1914, and Patent No. 1,172,864, dated February 22, 1916, which starter is characterized by a prime mover such as an electric motor, and
15 a transmission or drive for transmitting the power of the motor by means of a rotatable shaft, such as a screw shaft and a driving member such as a pinion mounted thereon, to the member of the engine to be started,
20 such as the fly wheel thereof. This drive comprises a screw shaft operated either directly from the armature shaft or indirectly thereby through gearing, and a pinion screw-threaded on such shaft and having
25 longitudinal movement thereon and rotary movement therewith. This drive also comprises a yielding driving connection such as a spring interposed in the driving connections at some point between the motor and
30 the driving member or pinion.

The object of my present invention is to provide a simple and reliable construction having the above enumerated characteristics and in which the yielding driving connection, such as a spring, is more or less dis-
35 associated from the screw shaft and pinion and associated more directly with the motor and the driving shaft thereof, which may be an extended armature shaft, and in which
40 such spring acts to permit of longitudinal movement of the driving shaft and to restore it to normal position. Another object is to shorten the length of the drive and make it compact in the direction of the
45 length of its shafts.

In the drawings Figure 1 is a sectional elevation of the transmission or drive embodying my invention; and Figs. 2 and 3 similar views illustrating modified forms of
50 construction.

Referring to the embodiment as herein shown, the starting motor which is represented in part at A is here provided with an extended armature shaft 1, passing
55 through a casing 2 and having a bearing at 3 in a casing A', which incloses the parts

of the drive. Such bearing, however, is not essential. Toward the outer end of this shaft there is secured by means of bolt 4 a collar 5 and to the bolt is anchored a coiled 60 spring 6 which constitutes the yielding driving connection. The other end of this spring is anchored to another collar 7 by means of a stud 8. This latter collar is loosely mounted or floats upon the shaft, 65 being capable of longitudinal movement thereon and rotary movement therewith, as well as a limited rotary movement independent thereof. This collar 7 carries a pinion 9 which as shown and by preference is made 70 separate therefrom and attached thereto in a suitable manner, although it might be made integral therewith. This pinion is mounted on the shaft 1 and has the same relative movements with respect thereto as 75 its collar 7. It is provided with a flange 10 so as not only to mesh with the large gear 11, but also to coöperate with a side of the rim thereof.

The gear 11 is adapted to drive the sec- 80 ondary shaft 13 which is here shown as (but not by necessity) a solid screw shaft. As shown this gear is secured in a suitable manner as by means of the screw threads 12 to the driving or screw shaft 13 whose central 85 portion is screw-threaded to receive the driving member or pinion 14. This pinion is adapted to mesh with the teeth 15^a on the periphery of the fly wheel of the engine to be started. The ends of the screw shaft 90 13 are plain and are received in the bearings 16 and 17, such shaft having an endwise movement in the bearings.

If desired, the pinion 14 might be made to move in the opposite direction, that is, 95 to the right for meshing, in which case the spring would be expanded in the longitudinal movement of the shaft 13, or, if desired, the gearing may be arranged at the other ends of the shafts 1 and 13, in which case 100 the spring would be expanded or compressed according to the adopted direction of movement of the pinion in meshing. These modified forms of construction are illustrated in Figs. 2 and 3 and hereafter 105 described.

Describing the operation of the device and starting with the parts in the normal position shown, when the motor is operated the power of the shaft 1 is transmitted 110 through the driving spring 6 to the pinion 9, thence through gear 11 to the screw shaft,

whereupon the pinion 14 will be advanced longitudinally of such shaft, that is, to the left and into mesh with the fly-wheel. When the pinion 14 has fully meshed and 5 has contacted the hub 11^a of the gear which acts as a stop, such pinion will rotate in unison with the screw shaft and will consequently rotate the fly wheel. When the engine starts on its own power such pinion 10 will be automatically demeshed.

In the event that the teeth of the pinion 14 and of the fly wheel should abut end to end, the screw shaft will yield longitudinally, that is, move bodily toward the right. 15 This movement is a yielding one against the tension of the spring 6, inasmuch as such movement will likewise carry the gear 11 in the same direction, thereupon moving the pinion 9 and head 7 in that direction against 20 the expanding tension of the spring 6. It is for accomplishing this function that the pinion 10 and gear 11 have the engagement shown for lateral movement in unison.

The construction shown is what is known 25 as the double reduction form of drive because of the gearing between the starting motor and the screw shaft. There are therefore two shafts, a primary shaft 1 and a secondary shaft 13, with the former of 30 which the yielding driving connection is associated and with the latter of which the driving pinion is associated. Obviously, the shaft 1 need not be the armature shaft but a shaft driven thereby in suitable manner. 35

In Fig. 2 the construction is the same as in Fig. 1 with the exception that the pinion in its advance longitudinal movement moves in the opposite direction, that is toward the 40 right, with the result that in the event of the abutting end to end of the pinion and the fly wheel teeth the screw shaft and the gear 11 will be moved slightly to the right, thereby correspondingly moving the pinion 45 9 in the same direction. Consequently these movements which are resisted by the spring 6 will cause an expansion thereof instead of a contraction as in the case of the construction in Fig. 1.

50 The other modified form of construction is illustrated in Fig. 3 which is the same as the construction of Fig. 1 with the exception that the gearing instead of being arranged adjacent the motor, that is at the inner ends of the shafts 1 and 13, is arranged at the other or outer ends of these shafts. According to this construction the longitudinal movement of the screw shaft and of the gearing is outwardly, that is, toward the 55 right,—in the event that the pinion and the fly wheel teeth should abut end to end and such movement will cause an expanding of the spring 6.

I claim:

65 1. The combination of a driving shaft,

yielding driving means mounted on said shaft, a second driving shaft, operating connections between said means and the latter shaft, and a driving member mounted on such latter shaft for longitudinal movement 70 thereof and rotary movement therewith.

2. The combination of a driving shaft, yielding driving means mounted on said shaft, a second driving shaft, operating connections between said means and the latter 75 shaft, and a driving member mounted on such latter shaft for longitudinal movement thereof and rotary movement therewith, said two shafts being mounted in parallel relationship. 80

3. The combination of a driving shaft, yielding driving means surrounding said shaft, a second driving shaft, operating connections between said means and the latter shaft, and a driving member surrounding 85 such latter shaft for longitudinal movement thereof and rotary movement therewith.

4. The combination of a driving shaft, a coiled spring encircling and secured at one end to the shaft, a second driving shaft, operating connections between it and the other end of the spring, and a driving member mounted on such latter shaft for longitudinal movement 90 thereof and rotary movement therewith. 95

5. The combination of a primary driving shaft, a driving device loosely mounted thereon, a coiled spring encircling said shaft and connecting between it and said device, a secondary driving shaft, a driven device 100 thereon driven by said driving device, and a driving member mounted on the secondary shaft for longitudinal movement thereof and rotary movement therewith.

6. The combination of a driving shaft, a driving member mounted loosely thereon and capable of limited independent rotary movement in respect thereto, driving means between said shaft and member, a second driving shaft, operating connections between said member and latter shaft, and a driving member mounted on such latter shaft for longitudinal movement thereof and rotary movement therewith. 105 110

7. The combination of a driving shaft, a driving member mounted loosely thereon and capable of limited independent rotary movement in respect thereto, driving means between said shaft and member, a screw-threaded driving shaft, operating connections between said member and screw-shaft, and a pinion mounted for longitudinal movement with respect to the screw-shaft and rotary movement therewith. 115 120

8. The combination of a driving shaft, a driving member mounted loosely thereon and capable of limited independent rotary movement in respect thereto, yielding driving means between said shaft and member, a screw-threaded driving shaft, operating 125 130

connections between said member and screw-shaft, and a pinion adapted to be driven by the screw-shaft and mounted for longitudinal movement with respect to the screw-shaft and rotary movement therewith.

9. The combination of a driving shaft, a driving member mounted thereon for independent rotary movement therewith, yielding driving means between said shaft and member, a second driving shaft, means for driving the latter shaft from said member, and a driving member mounted on said latter shaft for longitudinal movement thereof and rotary movement therewith.

10 15. 10. The combination of a driving shaft, a pinion loosely mounted thereon, a yielding driving connection between the shaft and pinion, a second driving shaft, a gear secured thereto and adapted to mesh with the pinion, and a driving member adapted to be rotated by the latter shaft and mounted for longitudinal movement with respect thereto and rotary movement therewith.

11. The combination of a driving shaft, 25 yielding driving means mounted on and co-operating with said shaft, a second driving shaft mounted for longitudinal movement, operating connections between said means and the latter shaft, and a driving member 30 mounted on said second shaft.

12. The combination of a driving shaft, a coiled spring encircling said shaft and operatively connected therewith, a second driving shaft mounted for longitudinal movement, operating connections between said spring and the latter shaft, and a driving member mounted on said second shaft.

13. The combination of a driving shaft, 40 a driving member mounted thereon for independent rotary movement therewith, yielding driving means between said shaft and member, a second driving shaft, means for driving the latter shaft from said member, and a driving member mounted on said latter shaft for longitudinal movement thereof and rotary movement therewith, said latter shaft and first-named driving member being mounted for endwise or longitudinal movement.

50 14. The combination of a driving shaft, a pinion loosely mounted thereon, a yielding driving connection between the shaft and pinion, a second driving shaft, a gear secured thereto and adapted to mesh with the pinion, and a driving member adapted to be rotated by the latter shaft and mounted for longitudinal movement with respect thereto and rotary movement therewith, said pinion being movable laterally along its shaft and the said second shaft being mounted for endwise movement.

15. The combination of a driving shaft, a pinion loosely mounted thereon, a yielding driving connection between the shaft and pinion, a second driving shaft, a gear se-

cured thereto and adapted to mesh with the pinion, and a driving member adapted to be rotated by the latter shaft and mounted for longitudinal movement with respect thereto and rotary movement therewith, said pinion being capable of bodily movement along its shaft and the gear together with its shaft being capable of endwise movement and the pinion and gear being interlocked for such longitudinal movement in unison.

70 16. The combination of a driving shaft, a pinion loosely mounted thereon, a yielding driving connection between the shaft and pinion, a second driving shaft, a gear secured thereto and adapted to mesh with the pinion, and a driving member adapted to be rotated by the latter shaft and mounted for longitudinal movement with respect thereto and rotary movement therewith, said pinion being capable of bodily movement along its shaft and the gear together with its shaft being capable of endwise movement and the pinion having a flange embracing a side of the gear.

80 17. The combination of a driving shaft, a driving member mounted thereon for independent rotary movement therewith, a coiled spring encircling said shaft and operatively connected therewith and to said member, a second driving shaft, operating connections between it and said member, and a driving member mounted on the latter shaft for longitudinal movement thereof and rotary movement therewith.

90 18. The combination of a driving shaft, a driving member loosely mounted thereon for independent rotary movement and for longitudinal movement thereon, a coiled spring encircling said shaft and operatively connected therewith and to said member, a second driving shaft, operating connections between it and said member, and a driving member mounted on the latter shaft for longitudinal movement thereof and rotary movement therewith.

95 19. The combination of a driving shaft, yielding driving means mounted on and co-operating with said shaft, a second driving shaft mounted for longitudinal movement against the action of said yielding driving means, operating connections between said means and the latter shaft, and a driving member mounted on said second shaft.

100 20. The combination of a driving shaft, a driving member mounted thereon for independent rotary movement therewith, a coiled spring encircling said shaft and operatively connected therewith and to said member, a second driving shaft mounted for endwise movement against the tension of said spring, operating connections between said member and second shaft, and a driving member mounted on the latter shaft for longitudinal movement thereof and rotary movement therewith.

21. The combination of a rotatable member, a driving member mounted for rotary movement therewith and longitudinal movement with respect thereto, a driven wheel connected with the rotary member for driving it, a driving wheel coöperating with the driven wheel, a motor, and a yielding driving means coöperating between the motor and driving wheel.
- 10 22. The combination of a screw shaft, a pinion mounted for rotary movement therewith and longitudinal movement with respect thereto, a driven gear wheel connected with the screw shaft for driving it, a driving gear wheel for driving the other wheel, a motor, and a yielding driving means co-
- 5 operating between the motor and driving gear wheel.
23. The combination of a screw shaft, a pinion mounted for rotary movement therewith and longitudinal movement with respect thereto, a driven gear wheel connected with the screw shaft for driving it, a driving gear wheel for driving the other wheel, said two gear wheels being mounted 20 to move axially together, a motor, and a spring driving connection between the motor and driving gear wheel, such spring being arranged to yieldingly resist said axial movement of the gear wheels.
